UNITED STATES PATENT OFFICE.

WILLIAM S. THOMSON, OF PLANTSVILLE, CONNECTICUT, ASSIGNOR TO THE H. D. SMITH & COMPANY, OF PLANTSVILLE, CONNECTICUT, A CORPORATION.

DESIGN FOR A SOLID WRENCH.

46,189.

Specification for Design.

Patented July 28, 1914.

Application filed November 17, 1911. Serial No. 660,907. Term of patent 3½ years.

To all whom it may concern:

Be it known that I, WILLIAM S. THOMSON, a citizen of the United States, residing at Plantsville, in the county of Hartford and State of Connecticut, have invented a new, original, and ornamental Design for Solid Wrenches, of which the following is a specification, reference being had to the accompanying drawing, forming part thereof.

Figure 1 is a plan view of a solid wrench,

showing my new design. Fig. 2 is an edge view of the same.

I claim:

The ornamental design for a solid wrench, as shown.

WILLIAM S. THOMSON.

Witnesses:

E. H. GALPIN,
GEO. R. BOND.
